US00D624018S

(12) **United States Design Patent**
Ishizuka et al.

(10) **Patent No.:** US D624,018 S
(45) **Date of Patent:** ** Sep. 21, 2010

(54) **STATOR FOR A VEHICLE ROTARY ELECTRIC MACHINE**

(75) Inventors: **Atsuo Ishizuka**, Nagoya (JP); **Shinji Kouda**, Kariya (JP); **Shinichi Ogawa**, Obu (JP)

(73) Assignee: **Denso Corporation**, Kariya (JP)

(**) Term: **14 Years**

(21) Appl. No.: **29/352,970**

(22) Filed: **Dec. 30, 2009**

(57) **CLAIM**

The ornamental design for a stator for a vehicle rotary electric machine, as shown.

DESCRIPTION

This application is also related to U.S. Design patent application Ser. No. 29/352,970 filed simultaneously on Dec. 30, 2009 with the present application and entitled “Stator for a Vehicle Rotary Electric Machine.” This application is also related to U.S. Design patent application Ser. No. 29/309,962 filed on Nov. 20, 2008 and entitled Stator for a Vehicle Rotary Electric Machine.

FIG. 1 is a front perspective view of a stator for a vehicle rotary electric machine showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.
